UNITED STATES PATENT OFFICE.

JAMES E. MERRITT, OF FARGO, NORTH DAKOTA, ASSIGNEE TO MICHAEL J. McQUIRE,
OF SUPERIOR, WISCONSIN.

OUTER GARMENT.

1,210,343.

Specification of Letters Patent. Patented Dec. 26, 1916.

Application filed October 3, 1915, Serial No. 798,823. Renewed October 26, 1916. Serial No. 123,651.

To all whom it may concern:

Be it known that I, JAMES E. MERRITT, a citizen of the United States, residing at Fargo, in the county of Cass and State of North Dakota, have invented new and useful Improvements in Outer Garments, of which the following is a specification.

This invention relates to outer garments and more particularly to union outer garments.

The principal object of the invention is the combination or association of overalls with the usual jumper jacket in such manner that the suit will be convenient of application and removal.

Another object of the invention is in properly reinforcing the garment at all points where excessive wear occurs and at the same time to make the garment more water proof.

Further objects of the invention will appear as the following description is read in connection with the accompanying drawing, which forms a part of this application, and in which:

Figure 1 is a front elevation. Fig. 2 is a rear elevation. Fig. 3 is a longitudinal section through one of the sleeves. Fig. 4 is a vertical section on the line 4-4 of Fig. 1 showing the seat flap lowered.

Referring more particularly to the drawing, 1 represents the body portion and 2 the trousers portion which is joined to the body by stitching or in any other permanent manner throughout the front half of the body. The body is open down the front, as is usual, and the marginal edges are joined together in any suitable manner. This opening extends throughout the length of the body portion and communicates with the fly 3 of the trousers, making a continuous opening from the neck of the garment to the crotch. The rear portion of the trousers part is formed into a flap 4, the upper marginal edge of which is buttoned to the back of the body portion, as shown at 5, and is also provided with belt loops 6 through which the belt 7 is adapted to extend. This belt also runs through loops 8 formed on the front of the trouser portion and is buckled in front, as is usual. It has been found in

practice that when the belt is used the wearer of the garment is permitted considerably more freedom in the arms.

The flap 4 is provided with two rear 55 pockets 9 while the front portion of the trousers has pockets 10 adjacent each side and a rear pocket 11 situated upon one leg.

The seat of the trousers and crotch are reinforced by a patch piece 12 and the knees 60 of the trousers are reinforced by patch pieces 13, making the seat and knees of the trousers double, as will be readily understood. The shirt or body portion is provided with a pocket 14 on one side and the sleeves are 65 reinforced by patch pieces 15 which extend from the collar to the bottom of the cuff on the outer and upper side of the sleeve and shoulder and are provided with flap pieces 16 which form a continuation of the pieces 70 15 and extend completely around the under-side of the sleeve from the elbow to the bottom of the cuff, said flaps having their meeting edges stitched together on the under side of the sleeve. The strips 15 and 75 flaps 16 and the reinforcing patches 12 and 13 not only serve to protect the garment against wear but also make these, the exposed parts of the garment, more water proof.

The garment is applied and removed in the same manner as the ordinary union suit and, therefore, needs no further description.

It will, of course, be understood that the body portion and trouser portion may be 85 constructed from continuous pieces of fabric so as to avoid stitching or otherwise joining the body and trousers at the waist line. This arrangement being common practice in undergarments of the combination 90 type should need no illustration herein.

What is claimed is:

1. A garment of the class described having a continuous reinforcing strip secured to the upper side of the shoulder and sleeve 95 of the garment and extending from the collar to the cuff, said reinforcing strip having flaps formed integral therewith and co-acting with the strip to inclose the sleeve from the elbow to the cuff.

2. A garment having a continuous reinforcing strip extending from the collar to

the cuff on the sleeve of the garment and secured to the upper face of the shoulder and sleeve, said reinforcing strip having flaps formed integral therewith and extending between the elbow and cuff, said flaps having their meeting edges stitched together on the underside of the sleeve.

In testimony whereof I affix my signature in presence of two witnesses.

JAMES E. MERRITT.
